UNITED STATES PATENT OFFICE.

PETER W. MURPHY, OF DETROIT, MICHIGAN, ASSIGNOR TO THE MURPHY ENGINEERING COMPANY, OF DETROIT, MICHIGAN, A CORPORATION OF MICHIGAN.

OILING SYSTEM FOR INTERNAL-COMBUSTION ENGINES.

1,332,948.

Specification of Letters Patent.

Patented Mar. 9, 1920.

Application filed June 24, 1918. Serial No. 241,657.

To all whom it may concern:

Be it known that I, PETER W. MURPHY, a citizen of the United States, residing at Detroit, county of Wayne, State of Michigan, have invented a certain new and useful Improvement in Oiling Systems for Internal-Combustion Engines, and declare the following to be a full, clear, and exact description of the same, such as will enable others skilled in the art to which it pertains to make and use the same, reference being had to the accompanying drawings, which form a part of this specification.

This invention relates to oiling systems for internal combustion engines, its object being to provide an efficient method of oiling the cylinders of the engine by a vapor of oil drawn into the cylinder through a breather from an external casing in which the oil vapor is produced. The several novel features of construction and general objects are hereinafter more fully described and claimed and the preferred form of the invention is shown in the accompanying drawings of a specific type of engine in which—

Figure 1 is a vertical longitudinal section of an engine showing my improved oiling system.

Fig. 2 is an enlarged sectional view of one end of the engine.

The engine here shown is of the multiple cylinder type having a series of cylinders 1 arranged in a circle about a central drive shaft 2, the longitudinal axes of the cylinders lying parallel with the axis of the shaft. There are two sets of cylinders oppositely disposed as shown in Fig. 1, and between the end of the cylinders is mounted a casing 4 in which is a cam 3 fixed to the shaft 2. The cylinders are each provided with pistons 5 and the piston rods 6 of oppositely disposed cylinders of the two series are rigidly connected to a slide 7 having rollers 8 engaging the cam. The slide is mounted in ways in the case 4 and the explosion of a charge at the head of a cylinder drives the piston inward and the opposite piston outward in its cylinder, the explosions in the opposite cylinders taking place in alternate relation as will be readily understood. In the arrangement here shown the piston rods move in a straight line on

the axis of the cylinder. The casing 4 is usually provided with a quantity of oil in 55 which the cam member and slide members operate. In view of the fact that, if these cylinders open into the case 4, oil will readily flow into the lowermost cylinders and flood the same with oil and due to the quantity of 60 oil used in the case 4 even the cylinders at the top of the casing, by reason of the splashing of oil in the case 4, will be provided with an excess amount of oil, it is necessary to prevent such over-supply. I have 65 therefore provided a baffle plate 9 for each series of cylinders covering the lower open ends thereof as shown, the baffle plate being secured in any approved manner as by being engaged between the flange of the case 4 and 70 casing for the cylinders. These baffles are each apertured opposite the center of each cylinder to allow the piston rod 6 to pass therethrough and are provided with a bearing 10 apertured to receive the rod and having a flange at one end as shown clearly in Fig. 2. The opposite end is threaded and a nut 11 is provided for securing the bearing in the baffle plate. By this arrangement of baffles the cylinders are closed to the case 4 80 and oil is prevented from being splashed thereinto.

To oil the said cylinders I have, in the construction here shown, provided an external case 13 encircling the case 4 and extending over the lower ends of the cylinder castings and secured in place therein as by a band 14 at each end. The cylinders each open into this chamber 15 provided by the shell 13 by means of a breather port 16 and the shell is open to atmosphere through a breather port 17 at the upper end thereof. By this arrangement the cylinders between the lower end of the piston and the baffle in each instance may draw in air on the up 95 stroke of the piston and expel air on the down stroke thereof. To efficiently oil these cylinders I have provided nozzles 18, a number of which may be employed if so desired, through which oil may be forced by pressure, the nozzles being arranged to spray the oil in the chamber 15 so that the air in passing back and forth into and out of the cylinders, becomes saturated with oil and the cylinders thus lubricated. The type of nozzle 100 18 is immaterial the object thereof being to

break the oil up into a fine spray, in which condition it may be carried by the air into the cylinders and an atomizer of any known type that will accomplish this purpose may be utilized.

By this arrangement it is readily seen that by breaking the quantity of oil delivered into the chamber 15 by the spraying devices the cylinders may be provided with the necessary amount of oil and by use of the baffle plates the central case 4 may be provided with an excess amount of oil without liability of flooding the cylinders. Oil may be introduced into the case 4 through the tube 20 indicated by dotted lines in Fig. 1.

I have here shown only one type of engine but the invention is applicable to various designs of engine of the internal combustion type in which the cylinders open at the lower end into a casing which is normally provided with oil liable to be splashed into or to flow into the cylinders in excess of the required amount. By closing the cylinders with a baffle of general character here shown and provision of a breather chamber separate from the oil retaining casing the amount of oil delivered to the cylinder may be regulated. In those types of engines in which the piston rod is in pivotal relation with the piston the type of bearing 10 here shown in the baffle plate will necessarily be altered in design to allow movement of the piston rod laterally relative to the axis of the cylinder.

Having thus briefly described my invention, what I claim is—

1. In an internal combustion engine, a cylinder, a piston therein provided with a piston rod, a case into which the rod extends for operation of the drive shaft, said case being adapted to be provided with a quantity of oil for supplying the operating parts therein, a baffle closing the cylinder to the case through which the piston rod extends, means for packing the rod to prevent passage of oil from the case into the cylinder, a chamber closed to the case there being a passageway provided between the chamber and the lower end of the cylinder whereby movement of the piston therein draws air through the chamber, said chamber being open to atmosphere, and means of providing a supply of oil in the said chamber.

2. In an internal combustion engine, a cylinder, a piston therein provided with a piston rod, a drive shaft, a case into which the rod extends for operative connection with the drive shaft, the case being adapted to be provided with a quantity of oil for lubrication of the parts therein, a baffle closing the cylinder to the casing preventing oil in the casing from passing into the cylinder, the piston rod extending through the baffle, means for packing the rod to prevent a material leakage of oil through the rod bearing

in the baffle, the cylinders being provided with a breather port at the lower end thereof, a chamber into which the port opens, and means for supplying an oil vapor in the said chamber.

3. In an internal combustion engine, a series of circularly disposed cylinders, a shaft extending centrally therebetween parallel with the longitudinal axis of the cylinders, pistons in the said cylinders provided with piston rods, a casing attached to the lower end of the cylinders, there being a driving connection in the said casing between the piston rods and shaft to cause rotation thereof by reciprocation of the pistons, the cylinders and shaft lying in horizontal position and the said case being adapted to receive a quantity of oil, means for preventing a flow of oil from the case into the cylinders comprising a baffle plate between the case and cylinder casting closing the lower open end of the cylinders to the case, the said baffle plate having an aperture on the axis of each cylinder through which the piston rod extends, a packing member for the rod in the said aperture in the baffle plate, an inclosing casing for the said case and lower end of the cylinders having an opening to atmosphere, the lower end of each of the said cylinders having openings leading into the chamber provided by said last named casing, said chamber and aperture through the cylinder walls providing a breather for the cylinders, and a series of spray devices by means of which oil may be introduced into the chamber in spray form.

4. A means for lubricating cylinders of an internal combustion engine, comprising in combination a cylinder, a casing connected therewith, means for preventing a flow of oil into the cylinder from the connected casing for the shaft, an air chamber open at one point to atmosphere, an aperture in the cylinder wall opening the said cylinder to the casing at the lower end providing a breather for the cylinder, and means for producing an oil vapor in the said chamber, the said breather providing the sole means of introduction of oil into the cylinder.

5. In a device of the character described, a plurality of cylinders, an oil vaporizing chamber surrounding the cylinders, a port for admitting air to said chamber and ports leading from said chamber to said cylinders.

6. In an engine of the character described, a cylinder, a piston, an oil vaporizing chamber surrounding the cylinder and a port connecting the cylinder to the chamber for admitting oil vapor to the cylinder on the advance stroke of the piston.

7. In an engine of the character described, a plurality of cylinders, an oil chamber, an air port in said chamber, nozzle

zles for spraying oil into said chamber and ports for permitting oil vapor to pass from said chamber into said cylinders.

8. In an engine of the character described, 5 a plurality of cylinders, an oil vaporizing chamber surrounding the cylinders and means to admit oil vapor from said chamber into said cylinders.

9. In an engine of the character described, 10 a main shaft, sets of opposed cylinders disposed around the shaft, a chamber partly surrounding said cylinders, ports connecting the chamber to the cylinders, means to produce oil vapor in said chamber and pistons movable in said cylinders and adapted 15 to draw oil vapor through the ports into the cylinders.

10. In an engine of the character described, a main shaft, cylinders disposed 20 around and parallel to the shaft interconnected pistons for the cylinders, an oil vaporizing chamber surrounding the cylinders and means to permit oil vapor to pass from the chamber unto the cylinders upon 25 movement of the pistons in either direction.

11. In an engine of the character described, a main shaft, sets of opposed cylinders disposed around the shaft, a casing

between the sets of cylinders, an oil vaporizing chamber surrounding the casing and 30 cylinders, and means to admit vapor from the chamber into each of the cylinders.

12. In an engine of the character described, a cylinder, an oil vaporizing chamber separate from the cylinder, and means 35 for admitting oil vapor from the chamber into the cylinder.

13. In an engine of the character described, a cylinder, an oil vaporizing chamber separate from but adjacent to the cylinder, 40 a port between the chamber and the cylinder and a piston movable in said cylinder and adapted to draw oil vapor from the chamber into the cylinder.

14. In a device of the character described, 45 a shaft, sets of opposed cylinders disposed around the shaft, a casing connecting the opposed cylinders, an oil vaporizing chamber surrounding the casing, ports admitting oil vapor from the chamber into 50 the cylinders and walls for preventing the passage of oil into the casing.

In testimony whereof I sign this specification.

PETER W. MURPHY.
